UNITED STATES PATENT OFFICE.

CHARLES S. MOORE, OF SHELBY, OHIO, ASSIGNOR TO THE CRYSTAL WAXING COMPANY, OF MIDDLETOWN, OHIO.

METHOD FOR HOLDING WAX SHEETS OF PAPER.

Application filed March 29, 1922. Serial No. 547,703.

To all whom it may concern:

Be it known that I, CHARLES S. MOORE, a citizen of the United States of America, residing at Shelby, in the county of Rich-
5 land and State of Ohio, have invented cer-
tain new and useful Improvements in a
Method for Holding Wax Sheets of Paper,
of which the following is a specification.

This invention relates to a holder for
10 waxed sheets of paper.

It is well known to the user of wax paper that difficulties are encountered in handling a package or a plurality of associated sheets of wax paper, on account of the smooth, 15 polished, or glossy surfaces thereof, which tend to permit the sheets to slip over each other rapidly and easily, thereby disturbing, disarranging, rumpling, mussing, and causing the package of sheets, if not restrained 20 or held in regular association with each other, to become uneven at the edges.

It is also well known to the user, that unless the package of wax sheets are held in uniform position, with relation to each other, 25 when withdrawing a single sheet from the package, it then becomes necessary to re-
arrange the sheets uniformly, requiring the excessive handling of the package of sheets or a separate sheet and the result of such 30 handling is an unsanitary condition of the sheet.

One of the objects of the invention is to provide a method of folding a plurality of wax sheets in overlapping relation to each other and providing a holder or container 35 to maintain the plurality of sheets in juxtaposition to each other and in regular, even and uniform sequence in the separation of a single sheet from the package without dis-
turbance, disarranging, wrinkling, rumpling, 40 and preventing the paper from curling at the corners, or otherwise being injured or confused.

Another object is to provide means of 45 keeping and maintaining through the medium of a holder and the novel folding of a plurality of wax paper used in combination therewith, the sheets of the package in good sanitary condition.

It is obvious that the sheets are rendered 50 unsanitary by continually handling and re-
arranging the wax paper after and before the withdrawal of a separate sheet from the package or pile, in the conventional method now in use.

These and other objects are attained by the combination of the holder and folded wax paper as illustrated in the accompanying drawings in which:

Fig. 1 is a cross sectional view of the 60 holder and folded wax paper.

Fig. 2 is an elevation of the holder.

Fig. 3 is an elevation of the holder showing the user withdrawing a single sheet from the package of sheets in the holder. 65

In the drawing, reference numeral 1 represents the central portion of a package or plurality of wax sheets, 2 and 3, the sides or ends, which are folded in uniform relation to each other, leaving spaces 4 and 5 between the 70 folded portions to permit the insertion of a finger for the purpose of withdrawing a single sheet from the package without disturbing or disarranging the sheets enclosed therein. It is of course obvious that the 75 sheets may be withdrawn by engaging the outermost sheet, as indicated in Fig. 3, instead of the innermost sheet from space 4.

The folded sheets are inserted in the folder 6 which is preferably formed rectangular in 80 shape and substantially flat, having an opening in one end to receive the folded pack or pile of wax sheets.

A flap 7 can be provided on the holder if desired, for enclosing the exposed ends of 85 the sheets, adjacent to the end opening.

Means are provided to maintain the plurality of sheets in uniform and even relation, and in sequence, to each other, while at the same time looped spaces are provided be- 90 tween the folded portions of the sheets to permit the insertion of the finger of the user to withdraw a single sheet at a time from the pile, until the pile is exhausted.

After a sheet is withdrawn from the pack- 95 age of sheets, the flap is turned over the exposed portion and sealed for sanitary trans-
portation and packing purposes.

It will be particularly noted that by in-
folding the respective sides of the assembled 100 sheets, and confining the sides and one end of the folded sheets while exposing one end, the sheets are held upright, and that there is absolutely no weight imposed by the packaging on any one sheet. That is to say, 105 no sheet is under any weight from the other sheets. This permits the convenient and absolutely unrestricted withdrawal of any innermost or outermost sheet, and hence permits the completion of the withdrawal 110

of a sheet without disturbing any other sheet of the package.

Attention is called to the fact that in forming the holder substantially flat and folding the wax paper flat, with loop therebetween, that the holder containing the wax paper can be packed, transported and stored in less space than is needed when the sheets are rolled or packed in the conventional manner now in use.

10 It will also be noted that the holder can be exhibited in a store or the like, more conveniently and in much less space than the conventional type of holder or package of wax paper sheets and further that a plurality of packages of wax sheets of paper of the shape and form described can be piled up more rapidly, more expeditiously and with greater facility than the conventional type of packages of wax sheets.

15 20 Attention is particularly directed to the fact that the package or container is designed for the purpose of packaging a plu-

rality of wax sheets to take the place of the present means of packaging wax sheets by 25 rolling same on a mailing tube or the like.

I claim:—

A package for wax sheets comprising a wrapper opened at one end to permit of the insertion of a plurality of wax sheets folded 30 first inwardly upon the central portion and then in opposed relation over the inwardly folded portion, said folded wax sheets being adapted to be inserted in the opened end of said package, whereby the tension of the 35 folded wax sheets exerts an outward pressure against the sides of the package holding the same in position under tension, thereby permitting the withdrawal of a single sheet at a time by the user through the manipulation of a single sheet by the thumb and forefinger of the user, as described and set forth.

In testimony whereof I affix my signature.

CHARLES S. MOORE.
